SNAP-ACTION SWITCH

Theodore Obszarny, Chicago, Ill., assignor to
 Guardian Electric Manufacturing Co., Chicago,
 Ill., a corporation of Illinois

Application March 15, 1943, Serial No. 479,180

2 Claims. (Cl. 200—67)

This invention relates to electrical switches of the snap-action type, adapted for rapidly making and breaking electrical circuits.

More particularly my invention is directed to snap-action switches of the blade type adapted for controlling either single or multiple circuits, and wherein such switches are usually of a relatively small compact construction, requiring a relatively small or light force to effect operation thereof. Due to the construction and character of operation of switches of this type as heretofore manufactured, they have necessarily been made as precision devices, requiring relatively small tolerances.

Certain switches of this general type, now available, are manufactured to such precision that it has been found desirable to perform certain operations on parts thereof after complete assembly of the switch. Such operations obviously increase cost of manufacture of the switch. Moreover the switches of this general type now available, practically all, include a movable member or element formed of a strip of spring metal which is initially deformed to provide what is known as a "sensitive area" to which area pressure is applied to produce flexing of the contact carrying portion of the member with a snap-action. Another construction of this general type utilizes a strip of spring metal which is initially bowed and held in such position so that it functions as a tension member. Still another type utilizes a strip of spring metal disposed in bowed formation between the free ends of two relatively movable actuating members and contact members of the switch.

All of such switch structures above referred to are of somewhat limited life because of the tendency of the strip of deformed or tensioned spring metal to crystallize at certain areas, due to frequent flexing actuation thereof.

Another objectionable characteristic of a switch of the last-mentioned type, is that in the event of excessive movement of the actuating member in one direction, the pressure between the switch contacts is reduced, and in some instances may even result in separation of the contacts. This condition is highly objectionable particularly in electrical circuits where it is important that after a contact is made, such contact be maintained for a certain period of time.

More specifically this invention is directed to improvements in a switch of the type disclosed in my copending application Serial No. 465,332, filed November 12, 1942, wherein I employ an elongated, resilient, movable contact member and

a cooperating resilient actuating member, and wherein one of the members is formed with a yoke portion disposed in surrounding relation to the free end portion of the other member, and wherein the free ends of said members are interconnected by a coil spring toggle serving to normally urge the free ends of the members apart.

The present invention is directed to improvements in snap switches of the type referred to in the foregoing paragraph, and has for one of its objects the provision of stop means for limiting the movement of the actuating member relative to the contact member, in one direction, to preclude separation of the switch contacts.

Another object is to provide improved stop means located in a position so as to be directly engaged by the actuating member for limiting movement relative to the movable contact member in one direction.

A further object is to provide a novel form and arrangement of stop means, which is in the nature of a cantilever member, positioned to be directly engaged by the actuating member for limiting its movement in one direction and by virtue of its construction, is adapted to permit a slight excessive amount of movement of the actuating member, as a safety factor, in the event that the actuating member is moved through too great a range.

Other objects and advantages of my invention will be apparent from the following description taken in connection with the accompanying drawings, in which:

Figure 1 is a top plan view of a switch embodying the present invention.

Figure 2 is a side elevational view of the switch.

Figure 3 is a vertical longitudinal section through the switch, taken substantially as indicated on lines 3—3 of Figure 1, showing the switch in another position of adjustment.

Figure 4 is a transverse sectional view through the switch, taken substantially as indicated on lines 4—4 of Figure 2.

Figure 5 is a fragmentary view, partly in section and partly in elevation, through the spring toggle connection, and taken substantially as indicated on lines 5—5 of Figure 2.

Figure 6 is a top plan view of a modified form of snap switch, embodying the present invention.

Figure 7 is a side elevational view of the modified form of my switch.

Figure 8 is a transverse sectional view through the switch taken substantially as indicated on lines 8—8 of Figure 7.

Figure 9 is an end elevational view of the contact making and breaking end of the switch.

Referring now to the switch construction disclosed in Figures 1 to 5 of the drawings, it will be noted that said switch is of the so-called "stack type" and includes a pair of superimposed, elongated, relatively rigid spaced apart contact bars or fingers 10 and 11 provided at their outer ends with contact buttons 10a and 11a respectively. The contact bars are rigidly mounted at their rear ends in insulated relation to each other between a plurality of insulated blocks or wafers 14.

Mounted between the contact bars 10 and 11 is a relatively resilient, elongated, movable contact switch member 15, provided at its free end, on opposite sides thereof, with contact buttons 15a and 15b adapted to cooperate respectively with the contact buttons 10a and 11a of the contact bars 10 and 11. The movable contact member 15 is mounted at its rear end in the stack of insulating blocks 14, in spaced insulated relation to the contact members 10 and 11 as seen in the drawings.

An elongated stamped yoke member 18, of resilient metal, which may be termed the actuating member, is fixedly mounted at its rear end in contact with the rear end portion of the movable contact member 15, in insulated relation to the contact bars 10 and 11, and has its outer or free end portion disposed in surrounding relation to the outer free end portion of the movable contact member. The relatively rigid contact bars 10 and 11 and movable contact member 15 are provided at their rear ends with laterally extending ears or lugs indicated at 10c, 11c and 15c respectively, to which may be conveniently connected, as by soldering, conductor wires of the electrical circuit to be controlled by the switch.

As is conventional in switches of this general type, the insulating blocks 14 and switch elements, as well as the yoke member 18, are each provided with a pair of aligned apertures in which are snugly fitted tubular insulating sleeves 19, so as to positively insulate the relatively rigid contact bars 10 and 11, and the movable switch member 15 from each other. To further rigidify the entire assembly, the stack of insulating blocks are capped, both at the top and bottom, by metal plates 20, and the total stack assembly is adapted to be secured to a convenient mounting by means of screws or bolts as indicated at 21.

It will be noted that the opening 18a of the yoke of the actuating member 18 is so dimensioned as to permit free relative movement of the free end portion of the movable contact member and actuating member relatively to each other.

The extreme outer free end portion of the movable contact member 15 is provided with a projection 15d, which is in the nature of a tapered tang, and the yoke member, at the adjacent inner edge of the opening, is provided with a projection 18d extending in the direction of the projection 15d, and which likewise is in the form of a tapered tang. The marginal edge portions of the respective members 15 and 18 immediately adjacent the respective projections serve as abutment shoulders.

The two members 15 and 18 are interconnected at their free outer ends by a toggle spring arrangement which includes a pair of flanged tubular eyelets 22 and 23 disposed in telescoping relation to each other, with their flanged ends surrounding the projections 15d and 18d of said members, and seated against said abutment

shoulders. A coil spring 25 surrounds the telescoping eyelets and abuts against the inner face of the flanges of the respective eyelets, tending to urge the eyelets apart, and likewise tending to urge the free end portions of the respective members 15 and 18 apart, as seen in Figures 2 and 3 of the drawings.

It will now be apparent that when force is initially applied to the outer end of the yoke member 18 for causing it to move from the position seen in Figure 2 of the drawings to the position shown in Figure 3 of the drawings, only sufficient movement is necessary to shift the yoke member 18 through and beyond the plane of the outer free end portion of the movable contact member 15, and as it passes beyond said plane, the movable contact member 15 moves, by virtue of the toggle spring connection, with a snap-action to separate the contact buttons 15a and 10a and cause firm contact engagement of the contact buttons 15b and 11a. It will be observed that during such movement of the actuating member 18, the coil spring 25 is slightly compressed, until the actuating member 18 approaches alignment with the flexible movable contact member 15, and as the free end of the actuating member passes over or beyond the plane of the free end portion of said contact member, the force of the compressed spring is expended to move the contact member 15 with a snap-action, to its opposite position of adjustment.

The extreme outer end portion of the actuating end portion 18 is provided with a plug 27 of insulating material, which is adapted to be engaged by any suitable element for applying the force or pressure to the actuating member for causing it to move from the position seen in Figure 2 of the drawings to the position seen in Figure 3 of the drawings.

It is to be understood that in the construction disclosed, the actuating member 18 is so constructed that when pressure on the plug 27 is released, the switch parts automatically resume a position as seen in Figure 2 of the drawings. It is to be understood however that the actuating member 18 may be so constructed that the switch parts may remain relatively stable in either of its two positions of adjustment as indicated in Figures 2 and 3 of the drawings, while still obtaining the same substantial advantages of the snap-action employed.

It will be apparent that by reason of utilizing a pair of telescoping eyelets the coil spring 25 is at all times guided during its movement from one position of adjustment to the other, as illustrated in the drawings, and precludes any lateral buckling of the spring during such movement. Thus the full balanced pressure of the coil spring is utilized for effecting the snap-action movement of the movable contact member 15, and also tends to maintain a uniform pressure between the contact buttons of the movable contact member 15 and the respective contact bars 10 and 11.

Because of the possibility of movement of the actuating member, in either direction, beyond what may be considered a proper or normal range, I provide suitable stop means in the form of relatively rigid elongated strips of insulating material as indicated at 30, mounted against the undersurface of the respective contact bars 10 and 11, and having their ends mounted in the stack assembly between the insulating blocks 14 so as to become a fixed part of the total assembly. As may be seen in the drawings, the insulating strips 30 are approximately of the same width

as the overall width of the actuating member 18 and are thus engageable by said member for limiting the movement thereof in either direction, as clearly seen in the drawings. The outer ends of the insulating strips 30 are formed with arcuate notches 31 so as to provide clearance around the contact buttons 10a and 11a respectively, to avoid possible interference with the making of proper contact with the contact buttons 15a and 15b of the movable contact member.

It will be observed that if the actuating member 18 is moved through too great a range, there is a normal tendency for the eyelets 22 and 23 to become disengaged and render the switch inoperative. Further, such excessive movement decreases the pressure of the coil spring 25 and thus decreases the effective pressure between the contact buttons. It is highly desired that the pressure between the contact buttons be of sufficient quantity, in order to insure making of good electrical contact. By virtue of the provision of the stop members 30, the actuating member is arrested at a proper position, at opposite ends of a desired operating range of movement, at which it is possible to obtain the use of the full force of the coil spring 25 for maintaining the contact buttons in firm engagement with each other. The stops also serve the purpose of eliminating the tendency to deform the actuating member 18, which may result by movement thereof through too great a range, and which would impair proper snap-action operation.

In the modified constructions illustrated in Figures 6 to 9 inclusive, there is employed an elongated base member 35 of suitable insulating material, which serves as the mounting for the snap-action switch. Rigidly mounted at one end of the base 35 is a relatively flexible elongated actuating member 36 and a relatively flexible elongated movable contact member 37, the latter being formed as a yoke and dimensioned with respect to the actuating member 36 so as to permit relative movement of the free end portions of the movable member relatively to each other. Said members are rigidly secured at one end, on said base by means of rivets 39. Mounted between the mounting ends of the respective members is a terminal plate 41 which includes an extension projecting around the adjacent end of the base and terminating at the underside thereof in an ear 41a.

The outer or free end of the movable contact member 37, which is of yoke formation, is provided at its opposite faces with contact buttons 37a and 37b, adapted to engage respectively with contact buttons 44a and 45a of a pair of contact strips 44 and 45, rigidly attached to the opposite end of the base 40, at the underside thereof, as clearly seen in the drawings. The lower ends of said strips terminate in ears 44b and 45b. Said terminal ears 41a, 44b and 45b are adapted to be connected, such as by soldering, to conductor wires for embodying the switch in an electrical circuit.

The free ends of the actuating member 36 and movable contact member 37 are provided with cooperating tangs or projections 36c and 37c and are interconnected by a spring toggle of the same general construction and arrangement as described in connection with the structure shown in Figures 1 to 5 inclusive of the drawings, and the action of the spring toggle is identical and it is therefore deemed unnecessary to again repeat the construction and operation thereof, and the corresponding parts are accorded similar reference numerals, supplemented by the letter "a."

In the position of the switch parts as seen in Figure 7 of the drawings, the resilient actuating member 36 is seated upon the head 48 of an operating plunger pin 49, slidably guided in a suitable recessed aperture formed in the base 35. It will be apparent that when the outer or exposed end of the plunger 49 is depressed, the head 48 impinging upon the flexible actuating member 36, moves the free end portion thereof through the opening of the yoke type movable contact member 37, and as it passes through and beyond the plane of the latter, the spring toggle arrangement operates with a snap-action to move the contact button 37a out of engagement with contact button 44a and causes engagement of the button 37b with the contact button 45a. When pressure on the pin 49 is removed, the switch parts move with a snap-action to the initial position as seen in Figure 7.

In the position of the switch parts seen in Figure 7 of the drawings, the head 48 of the plunger pin serves as a stop for limiting the position of the actuating member 36 in one direction. To limit the movement of said member in the other direction, I provide a relatively rigid cantilever stop 51, mounted at one end on top of the movable contact member 37, by means of the rivets 39. Thus the stop arrangement provided herein serves to limit the range of movement of the actuating member 36, so as to utilize and obtain the maximum advantage of the spring pressure of the toggle connection for insuring proper pressure between the cooperating contact buttons.

Although I have herein shown and described certain preferred embodiments of my invention, manifestly it is capable of further modification and rearrangement of parts without departing from the spirit and scope thereof. I do not, therefore, wish to be understood as limiting this invention to the precise forms herein disclosed, except as it may be so limited in the appended claims.

I claim as my invention:

1. A unitary, stack type, snap-action switch assembly comprising a pair of elongated, relatively rigid contact bars disposed in aligned, spaced apart relation, an elongated, resilient contact member movable into and out of engagement with said contact bars, an elongated, resilient actuating member, said members extending in alignment with said bars and rigidly connected at one end and the free end portion of one member being formed as a yoke and disposed in surrounding relation to the free end portion of the other member, said contact bars being rigidly connected at one end in insulated relation to said rigidly connected ends of said members, the free end portions of said members being provided with projections extending toward each other, a spring toggle connection including a coil spring mounted on said projections and urging the free ends of said members apart, whereby movement of the outer free end portion of the actuating member through and beyond the plane of the free end of the movable contact member effects movement of the latter with a snap-action into and out of engagement with said contact bars, and stop means positioned to be engaged by said actuating member for limiting its movement in one direction, said stop means comprising a relatively rigid strip of insulating material seated against the inner surface of one of said contact bars and rigidly connected at one end to the assembly of said bars and members.

2. A unitary, stack type, snap-action switch assembly comprising a pair of elongated, relatively rigid contact bars disposed in aligned, spaced apart relation, an elongated, resilient contact member movable into and out of engagement with said contact bars, an elongated, resilient actuating member, said members extending in alignment with said bars and rigidly connected at one end and the free end portion of one member being formed as a yoke and disposed in surrounding relation to the free end portion of the other member, said contact bars being rigidly connected at one end in insulated relation to said rigidly connected ends of said members, the free end portions of said members being provided with projections extending toward each other, a spring toggle connection including a

coil spring mounted on said projections and urging the free ends of said members apart, whereby movement of the outer free end portion of the actuating member through and beyond the plane of the free end of the movable contact member effects movement of the latter with a snap-action into and out of engagement with said contact bars, and stop means positioned to be engaged by said actuating member for limiting its movement in both directions, said stop means comprising a pair of relatively rigid strips of insulating material seated respectively against the inner surfaces of said contact bars and rigidly connected at one end to the assembly of said bars and members.

THEODORE OBSZARNY.
